UNITED STATES PATENT OFFICE.

ARTHUR ERNEST JERRAM AND JOSEPH GOULBOURN, OF LEICESTER, ENGLAND,
ASSIGNORS TO UNITED SHOE MACHINERY COMPANY, OF PATERSON, NEW JER-
SEY, A CORPORATION OF NEW JERSEY.

BUFFING-MACHINE.

1,119,828.

Specification of Letters Patent.

Patented Dec. 8, 1914.

Application filed December 11, 1909. Serial No. 532,628.

To all whom it may concern:

Be it known that we, ARTHUR E. JERRAM and JOSEPH GOULBOURN, subjects of the King of England, residing at Leicester, in the county of Leicester, England, have invented certain Improvements in Buffing-Machines, of which the following description, in connection with the accompanying drawings, is a specification, like reference characters on the drawings indicating like parts in the several figures.

This invention relates to grinding and polishing machines and will be described in connection with a machine for buffing the bottoms of boots and shoes.

It has been found that simultaneous rotation and reciprocation of the buffing roll tends to improve the surface produced on the work and to prolong the life of the abrasive covering of the roll. The rolls, however, are commonly mounted upon comparatively heavy shafts, and in machines as hitherto constructed the vibration caused by such reciprocation has proved objectionable. Accordingly one feature of the present invention comprises improved means for reciprocating the rotating shaft of such a machine. This and other features of the invention including certain details of construction and combinations of parts will be described in connection with an illustrative machine and pointed out in the appended claims.

Referring now to the accompanying drawings:—Figure 1 is a front elevation of a machine embodying this invention; Fig. 2 is a side elevation; Fig. 3 is a front elevation partly in section of the reciprocating mechanism and the brakes and pulleys for the roll shafts; Fig. 4 is a side elevation partly in section of the reciprocating mechanism; and Fig. 5 is a detail plan, also partly in section, of the device for actuating the oscillating levers.

Projecting from the frame of the machine is a bracket 1 carrying a casing 2 which contains the mechanism for reciprocating the roll shafts 3 and 5 which are located one on each side of the casing, the rolls on the shafts being shown at 6, and 106. It should be understood, however, that the number and character of said rolls are immaterial. The shafts 3 and 5 are shown as mounted in line in bearings 4, the mount-

ing being such as to permit longitudinal reciprocation.

Inasmuch as the means for reciprocating the roll shafts are identical only one set will be described. Fast to the shaft 5 is a pulley 9 by which said shaft may be rotated. A groove near the inner end of said shaft is engaged by a yoke 13 said shaft and yoke being thus capable of relative rotation but held from relative longitudinal movement. This yoke has projecting trunnions 16 upon which is pivoted a lever 19, said lever being of the floating type and being pivoted at 20 to a link 27 and at 22 to a movable member or slider 23. The link 27 has formed at its end a strap which encircles an eccentric 29 fast on a shaft 33. It is clear that with this construction and arrangement if the pivot 22 be held stationary while the eccentric 29 is actuated said pivot will serve as a fulcrum, and the shaft 5 will be reciprocated. If, on the other hand, the pivot 22 is permitted to move the pivot 16 will tend to remain stationary since the shaft 5 is much heavier than the slider 23 and since, as will be explained, means are provided for holding the shaft 5 stationary under such conditions. In order to control the movement of the slider 23 a controlling member 37 is mounted in a dove-tailed groove in the side of the casing 2, said member being provided with an aperture 41 adapted when placed opposite the end of the slider 23 to permit said slider to reciprocate. The upper part of the controlling member 37 is formed as a brake 71 having a shoe 72 to contact with the shaft 5 and thereby bring it to rest. With the parts in the position shown in Fig. 3 the slider 23 is held from movement and the brake 71 is released so that the shaft 5 may be reciprocated; while by pulling down on the actuating rod 45 which is pivoted to the member 37 the aperture 41 may be brought opposite the end of the slider 23 and at the same time the brake may be applied. The corresponding parts in the left hand portion of the figure are shown in this latter position. In order to compensate for wear and to insure that the member 23 may be held firmly in place when desired a set screw 47 is threaded through the casing and is provided with a lock nut as shown.

The mechanism for reciprocating the

shaft 3 is identical with that for reciprocating the shaft 5 except that it is oppositely arranged. The yoke 11 carries trunnions 15; the lever 17 is pivoted on these trunnions and also at 18 to the link 25 and at 24 to the slider 21, while the eccentric 31 which actuates the link 25 is fast to the shaft 33 and is arranged to move said link 25 in a direction opposite to that in which the link 27 is moved by the eccentric 29. A sliding controlling member 35 similar to the member 37 carries a brake 73, and is connected with an operating rod 43. A set screw similar to the set screw 47 but not shown is provided to coöperate with the slider 21. In order to insure that the shafts 3 and 5 shall not reciprocate when the sliders 21 and 23 are released springs 49 connect the trunnions 15 and 16. The pulleys 7 and 9 are operated by similar devices one of which will now be described. Referring to Figs. 1 and 2 the power shaft 38 carries a driving pulley 36, and around this driving pulley and the pulley 9 extends a loose belt 51. In order that this belt may be tightened when desired a bell crank controlling lever pivoted to the frame at 50 has mounted upon its arm 55 a tightener pulley 53 while the arm 56 is formed with a handle 57. It is desirable that the reciprocating mechanism should be thrown into operation approximately simultaneously with the rotating mechanism, and in order to accomplish this the rod 45 which operates the controlling member 37 and the brake 71 is connected with the arm 56 of the bell crank lever. Upon said lever is a projecting boss 63 through which the rod 45 passes while fast to said rod are two stops 65 and 67. Encircling the rod 45 and resting loosely upon the stop 67 is a coiled spring through which the brake 71 is yieldingly applied when the handle 57 is depressed, as shown in dotted lines, to render the actuating mechanism for the shaft 3 inoperative. A detent 59 with a suitable manipulating lever is provided on the arm 56 and engages a notched plate 61 fixed on the frame and so holds the bell crank controlling lever in adjusted position. The mechanism for rendering operative the rotating and reciprocating mechanisms for the shaft 3, as has been stated, is similar to that described above and comprises a bell crank lever provided with a handle 157 and with a tightener pulley 153 to tighten the belt 151 said lever having a sliding connection with the rod 43 and being encircled by the spring 169. The shaft 33 which drives the reciprocating mechanism carries at its end a pulley which is driven from the shaft 38 by a belt 34. The reciprocation of the shafts is of small extent and does not interfere with the operation of the belts 51 and 151. In order to remove the dust caused by the buffing operation hoods 77 and 177

partially inclose the buffing rolls while pipes 79 and 83 lead from said hoods to a suction device 81. The reciprocating mechanism is inclosed in the oil retaining casing 2, and in order to oil the parts a chain 75 is provided for lifting oil on to the shaft 33. The oil then passes through a spiral (not shown) cut in the journal to a suitable distributor which delivers it to the moving parts. 70

The present machine is designed to accommodate two operators. In operation and with the parts in the position shown in full lines in Fig. 2 one operator may at any time depress the handle 57 thereby loosening the belt 51. At the same time the boss 63 contacts with the spring 69 and lowers the member 37 until the recess 41 is opposite the end of the slider 23, the brake 71 fast to said member 37 being thus yieldingly applied to the shaft 5. The other operator 80 may likewise tighten or loosen the belt about the pulley 7 and throw into or out of operation the mechanism for reciprocating the shaft 3. It will thus be clear that the rotating and reciprocating means for either shaft 90 may be rendered operative approximately simultaneously and that the actuation of each shaft may be controlled independently of the other. 85

Although the invention has been set forth 95 in connection with a particular machine it should be understood that nothing herein contained is to be construed as limiting the invention in the scope of its application to the particular machine shown and 100 described.

The invention having thus been described, what is claimed and desired to be secured by Letters Patent is:—

1. A machine of the class described having, in combination, a plurality of buffing rolls, shafts upon which said rolls are mounted, means for rotating said shafts, levers connected with said shafts to reciprocate them, means for actuating said levers, and means for selectively rendering said actuation effective to reciprocate either of said shafts or ineffective to do so. 105

2. A machine of the class described having, in combination, a shaft, a buffing member mounted thereon, means for rotating said shaft, means for reciprocating said shaft, said last named means comprising a floating lever having an axis which is stationary during the reciprocation of said 115 shaft, and means for holding said shaft stationary when said axis of said lever is permitted to move.

3. A machine of the class described having, in combination, a plurality of shafts, buffing members mounted thereon, a yielding member connecting said shafts and means for rotating and reciprocating said shafts. 125

4. A machine of the class described hav- 130

ing, in combination, a pair of roll shafts, means for rotating said shafts, and means for reciprocating said shafts simultaneously in opposite directions, said means comprising two levers each capable of swinging about either of two axes, means for actuating said levers, and means for holding one of said axes stationary.

In testimony whereof we have signed our names to this specification in the presence of 10 two subscribing witnesses.

ARTHUR ERNEST JERRAM.
JOSEPH GOULDBOURN.
